CLAIM

The ornamental design for a full body personal protective shield, as shown and described.

DESCRIPTION

FIG. 1 is a front perspective view of the full body personal protective shield.

FIG. 2 is a back perspective view of the full body personal protective shield.

FIG. 3 is a front view of the full body personal protective shield.

FIG. 4 is a back view of the full body personal protective shield.

FIG. 5 is a left side view of the full body personal protective shield.

FIG. 6 is the right side view of the full body personal protective shield.

FIG. 7 is the top view of the full body personal protective shield.

FIG. 8 is the bottom view of the full body personal protective shield; and,

FIG. 9 is a front perspective view of the full body personal protective shield in environment.

The drawings contain a symbolic break. The portion between the break lines forms no part of the claimed design. The broken line portions are included to show environmental unclaimed subject matter only and form no part of the claimed design.
